FIG. 8 is a rear perspective view thereof shown supporting and carrying a bucket;
FIG. 9 is a front perspective view of a bucket carrier showing a second embodiment of my new design;
FIG. 10 is a front elevational view thereof;
FIG. 11 is a rear elevational view thereof;
FIG. 12 is a right side elevational thereof, the left side elevational view being a mirror image thereof;
FIG. 13 is a top plan view thereof;
FIG. 14 is a bottom plan view thereof;
FIG. 15 is a cross sectional view thereof taken along line 15-15 of FIG. 12;
FIG. 16 is a front perspective view of a bucket carrier showing a third embodiment of my new design;
FIG. 17 is a front elevational view thereof;
FIG. 18 is a rear elevational view thereof;
FIG. 19 is a right side elevational thereof, the left side elevational view being a mirror image thereof;
FIG. 20 is a top plan view thereof;
FIG. 21 is a bottom plan view thereof;
FIG. 22 is a cross sectional view thereof taken along line 22-22 of FIG. 19;
FIG. 23 is a front perspective view of a bucket carrier showing a fourth embodiment of my new design;
FIG. 24 is a front elevational view thereof;
FIG. 25 is a rear elevational view thereof;
FIG. 26 is a right side elevational thereof, the left side elevational view being a mirror image thereof;
FIG. 27 is a top plan view thereof;
FIG. 28 is a bottom plan view thereof;
FIG. 29 is a cross sectional view thereof taken along line 29-29 of FIG. 26;
FIG. 30 is a front perspective view of a bucket carrier showing a fifth embodiment of my new design;
FIG. 31 is a front elevational view thereof;

(Continued)

FIG. 32 is a rear elevational view thereof;
 FIG. 33 is a right side elevational thereof, the left side elevational view being a mirror image thereof;
 FIG. 34 is a top plan view thereof;
 FIG. 35 is a bottom plan view thereof;
 FIG. 36 is a cross sectional view thereof taken along line 36-36 of FIG. 33;
 FIG. 37 is a front perspective view of a bucket carrier showing a sixth embodiment of my new design;
 FIG. 38 is a front elevational view thereof;
 FIG. 39 is a rear elevational view thereof;
 FIG. 40 is a right side elevational thereof, the left side elevational view being a mirror image thereof;
 FIG. 41 is a top plan view thereof;
 FIG. 42 is a bottom plan view thereof;
 FIG. 43 is a cross sectional view thereof taken along line 43-43 of FIG. 40;
 FIG. 44 is a front perspective view of a bucket carrier showing a seventh embodiment of my new design;
 FIG. 45 is a front elevational view thereof;
 FIG. 46 is a rear elevational view thereof;
 FIG. 47 is a right side elevational thereof, the left side elevational view being a mirror image thereof;
 FIG. 48 is a top plan view thereof;
 FIG. 49 is a bottom plan view thereof;
 FIG. 50 is a cross sectional view thereof taken along line 50-50 of FIG. 47;
 FIG. 51 is a front perspective view of a bucket carrier showing an eighth embodiment of my new design;
 FIG. 52 is a front elevational view thereof;
 FIG. 53 is a rear elevational view thereof;
 FIG. 54 is a right side elevational thereof, the left side elevational view being a mirror image thereof;
 FIG. 55 is a top plan view thereof;
 FIG. 56 is a bottom plan view thereof; and,
 FIG. 57 is a cross sectional view thereof taken along line 57-57 of FIG. 54.

The broken line showing of a bucket is for the purpose of illustrating environmental structure and forms no part of the claimed design.
